Letters Patent

The Schedule referred to in these Letters Patent and making part of the same, containing a description in the words of the said Lewis Middle himself of his improvement in the Cover of witz Cisterns East piling &c.

24. 9320 X

1-15-1836

They should be inserted edgewise in the mould extending like radii from the apex to the bases or if the frame for the aperture occupy the central part of the mould, then they should extend from the frame to the base. After this preparation cast on the cement as before, and the cores will be divided into several wedge-shaped sections which when sufficiently seasoned may be removed at pleasure to the well-reddened cores which owing to their exact adaptation to each other produced by the above described manner of their separation they are easily put together forming a complete arch or dome.

The Improvement which this application claims to have invented consists in making said cores not for the well-reddened or other vessel where they are to be used, but in a shop or suitable manufactory in which they can have time to season, and from which they can afterwards be removed to the place of use where they can bear immediate exposure without risk of injury to which those in an unseasoned state are liable.
